UNITED STATES PATENT OFFICE.

WILLIAM BERNARD MICHEL, OF WILLOWSPRINGS, ILLINOIS.

RAILWAY-TRACK LAYER.

SPECIFICATION forming part of Letters Patent No. 744,870, dated November 24, 1903.

Application filed August 31, 1903. Serial No. 171,414. (No model.)

To all whom it may concern:

Be it known that I, WILLIAM BERNARD MICHEL, a citizen of the United States, residing at Willowsprings, in the county of Cook and

5 State of Illinois, have invented new and useful Improvements in Railway-Track Layers, of which the following is a specification.

This invention comprises particularly an apparatus to be used in connection with steam 10 shovels or excavators for moving and laying the track upon which the shovel is to travel.

The object of the invention is to produce an improved track-laying attachment for such excavators which will convey sections of the 15 track from the rear to the front, or vice versa.

The invention is particularly characterized by the fact that the apparatus will lift and carry a whole section of track without taking the track apart, thus affording a most rapid 20 and labor-saving apparatus.

Minor improvements in construction and arrangement will be apparent from the following description, in connection with the accompanying drawings, in which—

25 Figure 1 is a plan view of the apparatus, parts of the steam-shovel being indicated in outline; and Fig. 2 is a side elevation thereof.

Speaking generally, the device comprises a 30 track extending around one side of the car or body of the steam-shovel from one end to the other. This track is supported and spaced outwardly from the car a sufficient distance to allow the main track-section, rails, and 35 ties to pass beside the car, and a hanger rolls on the said track, carrying the track-section from one end of the car to the other.

Referring specifically to the drawings, the car of the excavator or shovel is indicated at 40 1, the shovel-boom at 2, and the floor-beams of the car at 3.

At 4 is indicated a boom projecting from the rear end of the car and supported by stay-rods 9, connected to the car-body.

45 The track 5, upon which the railway-sections are carried, is supported at its front and rear ends by connecting-rods 7 and 8, depending from the booms 2 and 4 at the median line of the car, and from these points the said 50 track is curved outwardly or sidewise, as clearly shown in Fig. 1, to bring it a sufficient distance beyond the side of the car to

afford a clear way for the passage of the railway-section. The track is supported in this position by braces 6, projecting from the car-beams. 55

The railway track-sections are indicated at 18, comprising rails and ties securely fastened together. The length of a section is preferably somewhat greater than the wheel-base 60 of the car of the excavator; but this is not essential, as the sections can be made of any length desired. Each section has at or about the middle thereof a set of four eyebolts, (shown at 20,) which take chains 17, whereby 65 the section is suspended from a piston-rod with hook 19, the piston of which works in a cylinder 19^a, hung from a roller-hanger 16, the roller of which travels on the track 5. The cylinder may conveniently be connected by 70 flexible hose-pipe to the boiler or pump of the steam-shovel and the lifting power obtained by steam or water pressure, the pipe being of sufficient length to permit the necessary travel of the hanger. It is evident that different lifting means may be provided by the 75 exercise of mechanical skill—such, for example, as a tackle arrangement connected to the winding-drum of the steam-shovel. I prefer, however, the cylinder apparatus described without in any way limiting my invention thereto. 80

When the track-laying device is not in use, the front section of the track 5 and the connecting-rod 7 are removed to permit the usual 85 operation of the steam-shovel.

In use in track-laying the hanger 16 is run to the end of the track over the railway-section to be moved and the chains connected to the eyebolts of the section. By means of the 90 lifting device the railway-section as a whole is raised and then can be pushed to the other end of the car, in which position it is laid and connected with the standing section of the track. Two sections of track will thus 95 be sufficient to permit the excavator to lay its own railway and to be moved backward or forward, as desired.

What I claim as new, and desire to secure by Letters Patent, is—

1. The combination with a car, of a track supported on and extending beside the car from front to rear thereof, a traveling hanger on the track, and means carried by the car to 100

lift and suspend a railway track-section from the hanger.

2. The combination with two railway track-sections, of a car supported on one section, and 5 means carried by the car to lift the other section as a whole, at one end of the car, and carry it beside the car to the other end.

3. The combination with a car having booms projecting at front and rear thereof, 10 of a track hung at its ends from said booms and extending beside the car, and a traveling hanger on the track, adapted to carry a railway-section from one end of the car to the other.

4. The combination with the car of a steam- 15 shovel or the like, of a track spaced from and supported by the car, and curved and extending from the middle line of the car at front and rear, along beside the same, and a traveling hanger and lifter on the track. 20

In testimony whereof I have signed my name to this specification in the presence of two subscribing witnesses.

WILLIAM BERNARD MICHEL.
